DANIEL J. BEMILLER, OF BUTLER, OHIO.

SAWDUST-CATCHING ATTACHMENT FOR CIRCULAR SAWS.

No. 922,840.

Specification of Letters Patent. Patented May 25, 1909.

Application filed April 11, 1907. Serial No. 367,518.

To all whom it may concern:

Be it known that I, DANIEL J. BEMILLER, a citizen of the United States, residing at Butler, in the county of Richland, State of Ohio, have invented certain new and useful Improvements in Sawdust-Catching Attachments for Circular Saws; and I do hereby declare the following to be a full, clear, and exact description of the invention, such as will enable others skilled in the art to which it app pertains to make and use the same.

The present invention relates to improvements in sawdust catching attachments for circular saws, and it aims to provide a device of that nature consisting of a receptacle having a discharge spout projecting from its bottom wall and connected with an exhaust pipe, which is in turn connected with a suction fan, the end walls of the receptacle tapering toward the discharge spout to direct the sawdust thereinto.

With the above and other ends in view, the invention consists in the construction, combination, and arrangement of parts, all as hereinafter more fully described, specifically claimed, and illustrated in the accompanying drawings, in which like parts are designated by corresponding reference numerals in both views.

30 Of the said drawings—Figure 1 is a front elevation of the complete sawdust removing apparatus. Fig. 2 is a transverse vertical section on the line 2—2 of Fig. 1.

Referring more particularly to the drawings, the numeral 5 designates a circular saw of conventional type, mounted upon its shaft 6, which is driven from any source of power (not shown), the lower portion of the saw extending into the sawdust-catching receptacle, 35 generally designated 7. This receptacle comprises a pair of semi-circular wooden side-pieces 8, which are arranged in spaced relation to each other, and are connected at their curved edges by a metal strip 9. Through 40 the strip 9 intermediate its ends is formed a discharge opening, which communicates with one end of a discharge spout 11, which extends tangentially from the receptacle, as shown, the upper side edges 10 of the spout being extended directly across the outer faces 45 of the sides 8, and secured thereto, as shown in Figs. 1 and 2. To the opposite end of

the discharge spout is connected one end of an exhaust pipe 12, whose opposite end is fitted in the inlet opening 13 of an exhaust fan 14.

While the side-pieces 8 of the receptacle have been above described as approximately semi-circular, it will be observed from Fig. 1 that the right-hand curved edge of the side 60 shown therein forms an arc of a circle, whose diameter is slightly greater than that of the left-hand arc, the connecting strip 9 being correspondingly bowed. Owing to this construction and to the fact that the under face 65 of the spout 11 forms a continuation of the right-hand arc, it will be apparent that the sawdust thrown against the strip 9 by the saw will be directed into the discharge spout. It will be likewise obvious that by reason of 70 such construction, it is correct to say that the receptacle is provided with end walls which converge toward the discharge opening.

It will be apparent from the foregoing that 75 when power is applied to the drive-shaft of the fan and the saw is running, all sawdust will be drawn through the discharge opening and spout into the exhaust pipe and through the latter into the fan, whence it is discharged 80 through the outlet pipe 15 thereof.

The sides of the receptacle are preferably formed of wood to prevent any injury to the saw teeth from contact therewith, in the event of the saw becoming loosened and wabbling on its shaft.

Further description of the invention and its operation is deemed unnecessary in view of the foregoing.

What is claimed, is—

In a device of the kind described, the combination with a rotary saw; of a sawdust catching receptacle into which the lower portion of the saw extends, said receptacle comprising a pair of spaced sides with the front portion concentric with the saw and the rear portion forming substantially an involute curve, a rim extending between said sides and each of the curved portions, said rims terminating with said curved portions at the bottom ends thereof to form a discharge opening, and a horizontal discharge spout adapted to be connected to a suction pipe, the rear bottom portion of the spout being

2

curved to form a continuation of the curved rear rim and the upper edge being substantially tangent to the path of the saw teeth whereby suction is obtained entirely below the path of the saw teeth and the full opening to the suction pipe is brought closely adjacent to the deepest part of said receptacle.

In testimony whereof, I affix my signature, in presence of two witnesses.

DANIEL J. BEMILLER.
